W. D. MAXIM ET AL

MECHANISM FOR THE CONTROL OF ELECTRIC STEAM GENERATORS

Filed Dec. 14, 1926

UNITED STATES PATENT OFFICE.

WILLIAM D. MAXIM AND EVERETT A. MAHANNAH, OF NEW YORK, N. Y., ASSIGNEES
TO INTERNATIONAL PAPER COMPANY, A CORPORATION OF NEW YORK.

MECHANISM FOR THE CONTROL OF ELECTRIC STEAM GENERATORS.

Application filed December 14, 1926. Serial No. 154,840.

This invention relates to the control of electric steam generators of the type in which a plurality of boilers or tanks are employed and the water therein heated by an electrode in each boiler supplied with the heating current from a common bus line, the amount of current acting on the water in each tank depending of course on the level of the water therein and the degree of submersion 5 of the electrode. The invention is particularly concerned with steam generators of this nature known in the trade as the "Kaelin three tank type", and the accompanying drawings show the invention applied to such 10 type, although it is applicable, as will be apparent to those skilled in the art, to steam generators of this type of other specific forms, and employing a greater or less number of tanks or boilers.

20 In the operation of steam generators of this class, it is highly desirable that the current supplied in amperes to one tank will not exceed that supplied to the other, or either of the other two when three are 25 employed, since any considerable percentage of "unbalance" would cause an overload of one phase of the generator, the cables, the switch equipment, etc., and would increase the liability of the power service supplying 30 the steam generators being interrupted by the protective relays which it is customary to install in the power line, such interruption resulting in loss of production.

The present invention aims to prevent the 35 occurrence of such objectionable conditions, and it consists of electrically actuated means, operating automatically to control the supply of feed water to the respective tanks, according to variations, within certain limits, which may occur in the amount 40 of current in amperes acting in the respective tanks, the said means acting to shut off the feed water to that tank or tanks in which the current supply increases by a given percentage beyond that of the other 45 tanks, and acting to again open the feed water supply when the current supply has been so far reduced as to "balance" that of the other tanks; whereby the current supply 50 to all of the tanks will be automatically maintained at the same ampere strength and the "balance" of the tanks preserved. In the specification to follow, the form and

construction of the parts by which the above described operations are brought about, will 55 be described in detail, and the novel features thereof pointed out in the appended claims.

In the accompanying drawings:

The figure is a diagrammatic view showing a battery of three electric steam genera- 60 tors with my invention applied thereto.

Referring to the drawings:

The steam generating boilers or tanks to be controlled are designated respectively by reference numerals 1, 2 and 3, there being 65 in the present instance as illustrative of the invention by way of example, three of these tanks, each equipped with an electrode 4 connected electrically respectively by leads 5, 6 and 7 to the three phases of a supply 70 bus line 8, electrical connections being provided between the tanks, and the latter grounded as usual so that the current will flow through the bodies of water between the electrodes and sides of the tanks and 75 will heat the same, all in the manner well-known in this art, it being understood of course that the amount of current in amperes acting on the water in a tank will depend upon the water level therein, and con- 80sequently upon the degree of submersion of the electrode.

The tanks are supplied with water from a feed water main 12 from which branch pipes 13, 14 and 15 lead to the bottoms of the re- 85 spective tanks. The branch pipes are equipped respectively with cut-off valves 16, 17 and 18 operatively connected with operating cores 19, 20 and 21 actuated by solenoid coils 22, 23 and 24, which coils are connected in electric circuits to be described more in detail later on, the said solenoids and cores constituting electro-magnetic 90 valve operating means.

Connected in series with the branch con- 95 ductors 5, 6 and 7 of the incoming bus line, are current transformers 25, 26 and 27 of the proper ratio to deliver a 5 ampere sec- 100 ondary current under the maximum load on the tank circuit or bus line, to secondary cir- 105 cuits 28, 29 and 30, which secondary circuits are connected to a differential relay 31.

This relay, which is of a well known com- 105 mercial type, is composed of three elements 32, 33 and 34, each element comprising an operating coil 35 and a retarding coil 36.

mounted respectively on horseshoe magnets 37 and 38, and a copper disk 39 carried by an operating shaft 39^a, and rotating between the pole pieces of the magnets. Each shaft 5 operates a switch plate 39^b, which at the end of the rotation of the shaft, makes contact with a pair of silver contacts, there being of course one pair of contacts for each element, a pair 40 for element 32, a pair 41 10 for element 33, and a pair 42 for element 34. These pairs of contacts are included respectively in electric circuits 43, 44 and 45, which circuits are connected in parallel respectively with operating coils 46, 47 and 15 48 of three single-pole contactors or switches 49, 50 and 51 of well known form, including each a fixed contact point 49^a and a movable contact arm 49^b.

The circuits 43, 44 and 45 are supplied 20 with electric current, in the present instance a direct current, from a power line by conductors 53, 54 and 55 branching from one side 52 of the power line and connected respectively to one of the ends of the operating 25 coils of the three single-pole contactors, the said conductors being furnished respectively with suitable resistances 53^a, 54^a and 55^a to prevent overload of the circuits when the power current is shunted around the 30 operating coils 46, 47 and 48 as will be presently described. Conductors 56, 57 and 58 lead from the other ends of said coils to contacts 59, 60 and 61 spaced respectively from contacts 62, 63 and 64 connected by 35 a common conductor 65 with the other side 52^a of the power line. Switches 66, 67 and 68 cooperate with the pairs of said spaced contacts in controlling the height of the water level, the said switches being operated 40 in the present instance by expansion tubes 66^a, 67^a and 68^a communicating at opposite ends respectively with the steam space and water in the several tanks and operating by 45 expansion and contraction, as steam or water enters the tubes, to move the switches and close or open the circuits through the contact points. The arrangement of the parts in the present instance is such that under normal 50 conditions of operation with the water level at the proper height, the switches will be held in engagement with the pairs of contact points, thereby closing the circuits, but in the event of the water rising to an undue level where it might flood the steam pipe, 55 the switches will be moved and disengaging the pairs of contacts the circuits will be opened, it being understood of course that there is one of these water level controlling switches for each tank, and that they are 60 operative independently of each other. As a result of this arrangement and construction of the parts, it will be understood that under normal operating conditions, the three operating coils of the single-pole contactors 65 will be energized by the current of the power

circuit traversing said coils through the normally closed circuits controlled by the high water level switch, under which conditions the circuits 43, 44 and 45 controlled by the differential relay will be open.

The solenoid coils 22, 23 and 24 which operate the feed-water valves, are connected at one end respectively by means of conductors 69, 70 and 71 to the side 52 of the power line, by a common conductor 72, the said 75 coils being connected at their opposite ends respectively by conductors 73, 74 and 75 to the fixed contact points 49^a of the three single-pole contactors 49, 50 and 51, the movable contact arms of which contactors 80 are connected respectively by conductors 76, 77 and 78 to the side 52^a of said power line.

As a result of the connection of the valve-operating solenoid coils and the single-pole contactors in the power line as described, 85 it will be understood that when the pole contactors are in closed position, the solenoid coils will be energized, and due to the connection of the armature cores 19, 20 and 21 with the respective feed water valves, 90 which connections in this form of the invention are such that when the cores are actuated by the energized solenoid coils, the valves will be held in opened position, said valves will be opened when the solenoid coils 95 are energized; and when said coils are de-energized, the valves will be closed by suitable springs provided for that purpose.

The operation of the parts so far described is as follows:

Under ordinary normal operating conditions, with the current supplied to the three tanks in "balance" or at the same valve, the three pairs of relay contacts 40, 41 and 42 will be in open position, and the operating 105 coils 46, 47 and 48 of the three single-pole contactors 49, 50 and 51 will be energized by the current of the power circuit traversing said coils as hereinbefore described, which will hold the movable contact arms of these pole contactors in contact with the fixed contact points of the same. The electric circuits through the valve-operating solenoid coils being thus closed, the cores connected with the valves will be actuated and the 110 valves held in open position, thereby admitting feed water to the several tanks. The water will continue to flow to the tanks as long as the aforementioned balanced condition exists, but in the event that the current to one of the tanks exceeds that of either of the other two, thereby destroying the balance previously existing, the torque of that operating coil of the relay connected in the secondary circuit of the tank in which the excessive current occurs, will overcome the torque of the corresponding retarding coil of the relay and will cause the associated disk to rotate in a direction to close the contacts of that particular element of the relay. 115 120 125 130

By this means the current from the power line, will be by-passed around that coil of the single-pole contactor which is in circuit with the solenoid coil of the tank receiving the excess of current, whereby the coil will be deenergized and its pole contactor will be opened, thereby deenergizing the solenoid coil, and permitting the feed water valve to close, so that the supply of water to the tank receiving the excess of current will be shut off. In by-passing the power current around the operating coil of the single-pole contactor as described, the current may be traced as follows, assuming for example that the excess of current occurs in tank 3. The circuit being closed by the differential relay actuated by the excess secondary current of the tank 3, the current from the side 52 of the power circuit will, due to the resistance offered by the coil 46, pass directly to the closed circuit 43 by conductor 53, and will leave said circuit by conductor 56 without traversing the coil 46, and will pass thence to contact point 59, switch 66, contact point 62 and by conductor 65 to the other side 52^a of the power circuit, the power current being thus shunted or by-passed around the coil and deenergizing the same. The feed water to the tank being shut off by the deenergizing of the coil 46 as described, the water remaining in the tank will boil down until a point is reached where the current flow through the water will be the same, or perhaps slightly less, than that of each of the other two tanks, and when this point is reached, the torque on the previously actuated operating coil of the relay being relieved, the associated disk will return to its former position, the previously closed relay contacts will be opened, the pole contactor closed due to the reenergizing of its operating coil, whereby the valve-operating solenoid coil will again be energized, and the feed water valve again opened to admit water to the boiler.

In practice the differential relay will be so adjusted or set that it will not operate to close the circuits controlled by it, unless the current in one tank exceeds that of either of the other two by 5 or 6%, since it has been found in practice that a smaller percentage of "unbalance" will not be seriously objectionable. It will be understood however that the parts may be set to operate under conditions involving a greater or less percentage of excess without departing from the spirit of the invention.

From the foregoing description and detailed construction and operation of the parts it will be understood that as long as a "balance" exists in the current acting in the tanks, no change in the operation takes place, but as soon as one tank carries more current than either of the other two, the feed water to the tank carrying the excess of current will be automatically and instantly

cut off, thereby preventing further increase of current in that tank; and when by reason of the lowering of the level of the water by the continued generation of steam without supplying more water, the current reaches 70 its former strength in "balance" with the current in the other tanks, the feed water will be instantly and automatically admitted again.

The improved system of control possesses 75 the advantages of simplicity, reliability, and low cost. It is operated directly by the factor which it is desired to control, viz, electric current, and it not affected by boiler scale, differences in density or height of the 80 water, variations in the length of the electrodes, or temperature, or pressure.

While in the arrangement of parts shown and described, the feed water valves are described as being held normally open by the solenoid coils when energized, under which conditions the water level control circuits are closed, the operating coils of the pole contactors energized, and the pole contactors closed, it will be understood by those 90 skilled in the art, that a reverse arrangement of these parts may be adapted, in which the valves may be held in open position when the solenoid coils are deenergized, and will be closed when the coils are energized, under 95 which conditions of course, the water level controlling circuits will be normally open, the operating coils of the pole contactors normally deenergized, and the pole contactors normally open. Under such a reversed arrangement of the parts, any excess of current in one tank, will, as before, act automatically to shut off the feed water to that tank.

While in the foregoing description and accompanying drawings we have set forth the invention in the particular detailed form which we prefer to adopt, it will be understood that these details may be variously changed and modified by the skilled mechanician without departing from the spirit of the invention; and further it will be understood that the invention is not limited to any particular form or construction of the parts, except in so far as such limitations are specified in the claims.

Having thus described our invention, what we claim is:

1. In combination with a plurality of electric steam generating tanks, means for supplying the same with electric current to heat the water therein, a feed water supply for each tank, an electrically operated means for each feed water supply, said several electrically operated means being supplied with 120 current from a common source, and an electrically operated controlling device for each of said electrically operated means supplied with current from said common source, and being adapted, by an excess of current in 125 130

one tank over that in another tank, to shut off the supply of feed water to the tank in which the excess of current occurs.

2. In combination with a plurality of electric steam generating tanks, means for supplying the same with electric current to heat the water therein, a feed water supply for each tank, a valve for each feed water supply, an electrically operated means for each valve supplied with current from a common source, and an electrically operated controlling device for each of said valve operating means supplied with current from said common source, and being adapted by an excess of current in one tank over that in another tank, to close the feed water valve of that tank in which the excess of current occurs.

3. In combination with a plurality of electric steam generating tanks, means for supplying the same with electric current to heat the water therein, a feed water supply for each tank, a valve for each feed water supply, an electrically operated means for each valve supplied with current from a common source, and an electrically operated controlling device for each of said valve operating means supplied with current from said common source, and being adapted by an excess of current in one tank over that in another tank, to close the feed water valve of that tank in which the excess of current occurs, said controlling device operating to open the valve when the current value again equals that of the other tank.

4. In combination with a plurality of electric steam generating tanks, means for supplying the same with electric current to heat the water therein, a feed water supply for each tank, a valve for each feed water supply, an electrically operated means for each valve supplied with current from a common source, an electric relay actuated by the heating current, and an electrically operated controlling device for each of said valve operating means, said controlling devices being supplied with electric current from said common source and being controlled in their action by said relay.

5. In combination with a plurality of electric steam generating tanks, means for supplying the same with electric current to heat the water therein, means for supplying feed water to the tanks, valves for controlling the flow of the water, electro-magnetic means for operating said valves, electric circuits including said means and supplied with current from a power line, electric switches in said circuits controlling the flow of the current thereto from the power line, an electric relay adapted to be operated by the heating current, and normally open circuits including said switches and adapted to be closed by the relay when actuated by the heating current.

6. In combination with a plurality of electric steam generating tanks, a bus line for supplying the same with electric current to heat the water therein, circuits supplied with secondary current from the bus line circuit, a differential relay connected to said secondary circuits and operated thereby, means for supplying the tanks with feed water, valves for controlling the flow of the water, electro-magnetic means for operating the valves, electric circuits including said means and supplied with current from a power line, and means actuated by said relay for controlling the supply of the current from the power line to the circuits of the valve operating means.

7. In combination with a plurality of electric steam generating tanks, means for supplying the same with electric current to heat the water therein, means for supplying feed water to the tanks, valves for controlling the flow of the water, electro-magnetic means for operating the valves, electric circuits including said means and supplied with current from a power line, electric switches in said circuits for controlling the flow of current thereto from the power line, operating coils for said switches, normally closed circuits connected with the power line and including said operating coils, normally open circuits including said operating coils and adapted when closed to shunt the power current around said coils, and an electric relay adapted to be actuated when the current in one tank exceeds that in another and operating when so actuated to close the normally open circuit connected with the coil of that switch which controls the circuit operating the valve of the tank in which the excess of current occurs; whereby under normal conditions of operation the several coils of the switches will be energized and the feed water valves will be maintained in open position, but when an excess of current in one tank occurs, the power circuit being shunted around the operating coil of the switch controlling that tank, the said coil will be deenergized and the feed water valve closed.

8. In combination with a plurality of electric steam generating tanks, means for supplying the same with electric current to heat the water therein, means for supplying feed water to the tanks, valves for controlling the flow of the water, electro-magnetic means for operating the valves, electric circuits including said means and supplied with current from a power line, electric switches in said circuits for controlling the flow of the current thereto from the power line, operating coils for said switches, normally closed circuits connected with the power line and including said operating coils, means in said normally closed circuits adapted to be operated to open the circuits when the water in the tanks rises to a predetermined level,

normally open circuits including said operating coils and adapted when closed to shunt the power current around said coils, and an electric relay adapted to be actuated when 5 the current in one tank exceeds that in another and operating when so actuated to close the normally open circuit connected with the coil of that switch which controls the circuit operating the valve of the tank 10 in which the excess of current occurs.

9. In combination with a plurality of steam generating tanks, means for supplying the same with electric current to heat the water therein, means for supplying feed water to the tanks, valves for controlling the flow of the water, electro-magnetic means for operating the valves, electric circuits including said means and supplied with current from a power line, electric switches in 15 20 25 30 said circuits for controlling the flow of the current from the power line, operating coils for said switches, normally closed circuits connected with the power line and including said operating coils, normally open circuits also including said operating coils and adapted when closed to shunt the power current around the coils, and means adapted to be actuated when the current in one tank exceeds that in another and operating when so actuated, to close the normally open circuit

connected with the coil of that switch which controls the circuit operating the valve of the tank in which the excess of current occurs.

10. In combination with a plurality of 35 electric steam generating tanks, means for supplying the same with electric current to heat the water therein, valves for controlling the flow of the water, electro-magnetic means for operating the valves, electric circuits 40 including said means and supplied with current from a power line, electric switches in said circuits for controlling the flow of the current thereto from the power line, operating coils for said switches, circuits connected 45 with the power line and including said operating coils, other circuits including said operating coils and adapted to shunt the power circuit around said coils, and an electric relay adapted to be actuated when the 50 current in one tank exceeds that in another, and operating when so actuated to shunt the power circuit around the coil of that switch which controls the circuit operating the 55 valve of the tank in which the excess of current occurs.

In testimony whereof, we have affixed our signatures hereto.

WILLIAM D. MAXIM.
EVERETT A. MAHANNAH.
